INSULATED SUPPORT FOR ELECTRIC CABLES

John I. Ellmann, Washington, D. C., assignor to
Ellmann Inc., Washington, D. C.

Application April 29, 1932, Serial No. 608,279

2 Claims. (Cl. 173—314)

This invention relates to means for suspending an electric current conducting cable from a messenger cable or other support.

One of the objects is to provide a simple article 5 of this character that can be inexpensively manufactured, is readily applied both to the conducting and supporting cables with ease and expedition, and without the necessity of the employment of tools, thus making it particularly handy 10 for workmen.

A further and important object is to provide a structure that is adapted to be easily opened for the admission of the cable without danger of the parts becoming detached, and when in position 15 and supporting a cable, is effectively locked against dismemberment and disengagement from its support.

The preferred embodiment of the invention is 20 illustrated in the accompanying drawing, wherein:

Figure 1 is a side elevation of a portion of a conducting cable and messenger cable with the former suspended from the latter by the new device.

Figure 2 is an end elevation of the suspending device.

Figures 3 and 4 are cross sectional views respectively on the lines 3—3 and 4—4 of Figure 2.

In the embodiment disclosed, an insulator is 30 provided made up of duplicate sections 6, which are generally semi-circular in form. Each is provided with an internal passageway 7 that together produce an opening for the passage of the cable, which opening may be of cross sectional 35 area, conforming to the shape of the cable. On one side of the passageway 7 of each section there is formed a socket 8, and on the other side the section is provided with an outstanding lug 9. The periphery of the insulator is provided with 40 a groove 10, the main portions of which are outwardly restricted, or in other words, these portions are of dovetail formation in cross section, as will be clear by reference to Figure 3.

A suspending member is provided, which is 45 preferably formed of a single piece of metal and includes a ring portion 11 that is of dovetail form in cross section, and is engaged in the groove 10. Obviously this formation causes the ring to have an interlocking engagement with the section, so that it cannot be detached laterally. By 50 rotating the sections, however, and expanding the ring these insulator sections may be removed or placed in position. The ring terminates in convergent portions 12 extending out of the groove 55 10, and providing arms, the outer portions 13 of

which are divergently disposed, providing between them a throat 14. Each of the arms 13 terminates in a hook 15 that is turned outwardly away from the other arm and downwardly.

As will be clear by reference to Figure 2 the 60 joints 16 between the insulator sections are vertically disposed so that the upper joint lies in a plane between the arms 12—13 and below the downwardly tapered throat 14. A portion of a current-conducting cable is shown at 17, and an 65 overhanging messenger or supporting cable is shown at 18.

In applying the device, it will be evident that if the current-conducting cable is passed downwardly through the throat 14, it will spread apart 70 the arms 12—13 and will open the upper joint 16 between the insulating sections. In other words, by spreading the arms sufficiently apart, the cable 17 can be passed through the joint 16 and into the opening 7. The insulator sections 75 cannot fall out of the ring because of their interlocking mounting thereon. When the cable 17 is in position, it is only necessary to press the arms 13 towards each other and bring the hooks over the support or messenger cable 18, 80 whereupon the device will be effectively locked in position and the insulator sections held closed around the cable.

Inasmuch as the two sections 6 of the insulator are duplicates, but one form is necessary 85 for both. There are thus only two distinctively different parts required in production, to wit, the insulator and the suspending member. As shown the dovetail form of the latter extends only around the portion engaged with the insulator sections. The remaining portion forming the arms 12—13 and the hooks 15 are preferably smaller in cross sectional area and may be square as will be clear by reference to Figure 4.

From the foregoing, it is thought that the 95 construction, operation and many advantages of the herein described invention will be apparent to those skilled in the art without further description, and it will be understood that various changes in the size, shape, proportion and 100 minor details of construction may be resorted to without departing from the spirit or sacrificing any of the advantages of the invention.

What I claim, is:—

1. A cable hanger for overhead support from 105 a messenger cable or the like comprising a suspending member having a lower ring-like portion with upstanding arms that can be relatively moved apart to permit the entrance of a cable 110 to be suspended, said arms having means at

their upper ends for engagement over a messenger cable or the like and suspending the hanger therefrom, and an insulator member located in and supported by the ring-like portion, said insulator comprising sections defining a passageway for the cable to be suspended by the hanger and comprising separable sections, each associated with one of the arms and having a joint between them that extends upwardly between the arms and opens when the arms are separated to permit the entrance therethrough to the passageway of a cable passed between the arms, said arms when suspended from the messenger cable being held against separation and thereby holding the insulator members together about the cable located in the passageway.

2. A cable hanger for overhead support from a messenger cable or the like comprising a suspending member having a lower ring-like portion with upstanding arms that can be relatively moved to separated positions to permit the entrance of a cable to be suspended, said arms hav-

ing lower portions upwardly convergently disposed and their upper portions upwardly divergently disposed and terminating in outwardly turned hooks for opposite engagement over a messenger cable or the like and suspending the hanger therefrom, and an insulator member located in and supported by the ring-like portion below said convergently disposed portions of the side arms, said insulator comprising sections defining a passageway for the cable to be suspended by the hanger and comprising separable sections, each associated with one of the arms and having a joint between them that extends upwardly between the arms and opens when the arms are separated to permit the entrance therethrough to the passageway of a cable passed between the arms, said arms when hooked over a messenger cable clamping the insulator sections together about a cable in the passageway and holding the upwardly extending joint between said sections against opening.

JOHN I. ELLMANN.
